UNITED STATES PATENT OFFICE

ANTOINE VÉRICEL, OF BALDWIN, NEW YORK, ASSIGNOR TO DOEHLER DIE-CASTING CO., A CORPORATION OF NEW YORK

DESIGN FOR A RADIO LOUD-SPEAKER OR THE LIKE

Application filed May 1, 1929. Serial No. 31,059. Term of patent 3½ years.

To all whom it may concern:

Be it known that I, ANTOINE VÉRICEL, a citizen of the Republic of France, and a resident of Baldwin, in the county of Nassau and State of New York, have invented and produced a certain new, original, and ornamental Design for Radio Loud-Speakers or the like, of which the following is a specification, reference being had to the accom-

panying drawings, forming part thereof, wherein—

Fig. 1 is a front view of my new design, and

Fig. 2 is a plan view thereof.

I claim:

The ornamental design for a radio loud speaker or the like, as shown.

ANTOINE VÉRICEL.
